UNITED STATES PATENT OFFICE.

JACQUES SENN, OF NEW YORK, N. Y.

LEAD-PENCIL.

SPECIFICATION forming part of Letters Patent No. 269,724, dated December 26, 1882.

Application filed March 1, 1882. (Model.)

To all whom it may concern:

Be it known that I, JACQUES SENN, of the city, county, and State of New York, have invented a new and Improved Lead-Pencil, of which the following is a full, clear, and exact description.

My invention relates to the class of lead-pencils in which the lead is clamped in any desired position by means of a spring-actuated clamp. Reference is to be had to the accompanying drawings, forming part of this specification, in which similar letters of reference indicate corresponding parts in all the figures.

Figure 1 is a longitudinal section of my improved pencil; and Fig. 2 is a detail view of the clamping device, and Fig. 3 is a transverse section taken on line *x x* in Fig. 1.

My invention is embodied in a guide for the pencil-lead, made of a single piece of metal doubled upon itself, forming a split tube for the lead, with lateral double wings extending along a portion of the length of the tube, a spring clamping-lever being pivoted between the wings upon one side of the tube, the whole being combined with a tube or casing forming an abutment for the spring of the lever and inclosing the working parts.

A plate of steel or other suitable material is cut and stamped or pressed in the usual and well known way, so as to form the two sides *a b* of the tube *A* and the two double wings *B C*. The wing *B* bears against the inner surface of the casing *D*, and acts simply as a support for the tube *A*, and the two parts of the wing *C* act as supports for the opposite side of the tube and receive the pivot *d* of the clamping-lever *E*. The clamping-lever *E* is serrated on the inner face of its shorter lower arm, and the extremity of this arm is made thin and bent back over the outer surface of the lever, forming a spring, *e*, which bears against the inner surface of the casing *D*, and forces the serrated face of the lever *E* into contact with the

lead *e*, contained in the tube *A*, and at the same time retains the tube within the casing. 45 There is an opening in the side of the tube *A* to admit the serrated end of the lever *E* for this purpose. The upper and longer arm of the lever *E* is provided with a rounded finger-piece, *f*, which projects through an opening in 50 the casing *D*, so that it can be conveniently pressed by the finger or thumb when it is desired to move the serrated portion of the lever for the purpose of adjusting the lead in the pencil. The casing *D* in the present instance 55 is provided with a hollow wooden handle, *F*, capable of receiving the portion of the lead extending above the upper end of the tube *A*; but the invention is not confined to this construction, as the casing *D* may be extended to 60 form a handle.

Having thus described my invention, I claim as new and desire to secure by Letters Patent—

1. In a lead-pencil, the tube *A*, having wings *B C*, and the serrated spring-lever *E*, in combination with the casing *D*, as herein specified. 65

2. In a lead-pencil, the combination with the tube *A* and the casing *D*, of the clamping-lever *E*, provided with the spring *e*, made integral therewith, and bent back over the outer surface of the same, substantially as herein shown and described, whereby the said spring serves the double purpose of forcing the lever against the lead and retaining the tube in the casing, as set forth. 70

3. In a lead-pencil, the combination, with the casing *D*, of the tube *A*, formed from a single sheet of metal, and provided with the double wings *B C* and the clamping-lever *E*, pivoted between the two parts of the wing *C*, substantially as and for the purpose set forth. 80

JACQUES SENN.
